UNITED STATES PATENT OFFICE

2,177,155

ATHLETIC SHOE

Isadore Shapiro, Chicago, Ill., assignor to The Athletic Shoe Company, Chicago, Ill., a corporation of Illinois

Application October 11, 1935, Serial No. 44,500

4 Claims. (Cl. 36—59)

My invention relates to athletic shoes and has to do more particularly with cleated shoes, such as are used in various games such as football, base ball, track, golf, etc., as well as for mountain climbing. Shoes embodying my invention are also of special value for walking on ice or other slippery surfaces, and find an important application in connection with logging and other activities where a sure grip on the ground or other surface is desired.

A particular object of my invention is to provide a shoe having detachable cleats or tread members, said shoe being so designed as to be especially simple in construction, inexpensive to fabricate, and highly efficient, whereby the cleats or tread members will be difficult to remove by accident or in ordinary use but may be readily detached and replaced when desired.

In general, an object of my invention is to provide an improved athletic shoe which will be entirely satisfactory for the purposes desired.

It has been the practice in the past to provide athletic shoes with steel plates attached to or embedded in the sole thereof and also with tread members detachably secured to the sole. However, it has been considered necessary heretofore to provide special means for attaching the tread members to the sole. Thus, for example, in Sternaman Patent No. 1,531,764, granted March 31, 1925, interiorly threaded studs are inserted in the sole of the shoe and the treads are screwed to these studs. Because of danger of the studs loosening and pushing up into the wearer's foot, additional clamping devices were suggested, as shown in Hart Patent No. 1,025,087, granted April 30, 1912. Again, in Riddell Patent No. 1,602,453, granted October 12, 1926, the shoe sole is provided with a "substantially inflexible steel plate" which has integral, enlarged bosses which are tapped to provide threaded sockets for the attachment of the cleats.

All of these prior art devices have serious disadvantages. An important one is that such arrangements greatly reduce the resilience of the sole, which should be as high as possible when a player is running, consistent with sufficient stiffness to maintain the cleats or treads in position. A further important disadvantage of such prior art structures is that the weight of the shoe is greatly increased by providing special sockets, studs, or other attaching devices for each cleat. Obviously, the weight of an athletic shoe should be as low as possible. Still another disadvantage of such devices lies in the excessive cost of materials and labor.

I have discovered, after extensive experimentation, that a resilient spring-steel plate will serve adequately for the anchorage of detachable cleats or tread members of any type without the use of any intermediate attaching device such as have heretofore been considered necessary by those skilled in this art. I have thus been able to produce a shoe fully as rugged and efficient as any of the prior art structures but considerably lighter in weight, more flexible, less expensive to fabricate, and possessing numerous other advantages such as will readily appear to those skilled in the art.

My invention will be more clearly apprehended by referring to the attached drawing illustrating certain embodiments of my invention, wherein:

Figure 1 is a side elevational view of a football shoe embodying my invention, part of the shoe being cut away to illustrate the construction more clearly.

Figure 2 is a perspective view of a football cleat of the type shown attached to the shoe in Figure 1.

Figure 3 is a fragmentary bottom plan view of the sole of the shoe shown in Figure 1.

Figure 4 is an enlarged detailed section through the sole of the shoe of Figure 1, and an attached cleat.

Figure 5 is a fragmentary side elevation of another type of shoe embodying my invention which is especially useful for running, golf, mountain climbing, logging, or other activities where a sharp grip is desired, part of the shoe being cut away to show the connection between the cleat and sole.

Figure 6 is a perspective view of the form of tread member shown attached to the shoe in Figure 5.

Figure 7 is a bottom plan view of the sole of a baseball shoe embodying my invention.

Figure 8 is a sectional view taken substantially on the line 8—8 of Figure 7, and

Figure 9 is a fragmentary sectional view of one form of screw forming an element of my invention.

Referring first to Figures 1—4, inclusive, the numeral 10 indicates a football shoe having an upper 12 and a sole 13. A heel tap 14 and a sole tap 15 are preferably provided and secured to the sole 13 by means of stitching 16 or other suitable means. The upper 12 may be secured to the sole by means of stitching 17 in the usual manner. There is also provided the usual insole 18 and sock-lining 19.

The sole is provided with a steel plate, indicated at 20, which may be secured to the sole at any suitable point, as on the outside, inside, or interior. I prefer to embed the plate 20 between 5 the sole 13 and the tap 15, but it will be understood that the location and arrangement of the plate may vary considerably. The plate, as shown in Figure 3, may follow the general contour of the sole or, if desired, the plate may be skeletonized to increase flexibility or may take various 10 other shapes. A similar plate 20' is arranged in the heel as shown in Figure 1.

The plates 20 and 20' are preferably formed of very thin and highly resilient tempered spring- 15 steel, such as will readily return to its normal shape when bent or otherwise distorted, without taking a permanent set. Said plates may be of any gauge or thickness to give the desired resilience. For example, a thickness of .017 to .025 20 inch is preferred.

Attached to the shoe sole are a plurality of cleats indicated generally by the numeral 23. These cleats comprise a molded frusto-conical member 24 which may be formed of hard rubber 25 or a rubber-fiber mixture, bakelite, or any other desired or suitable plastic material, such as is well known in this art. Embedded in the molded member 24 is a stud 26 which may be provided with annular grooves 27 or other deformations 30 designed to improve the bond between the stud and the molded member. Extending beyond the molded member 24 the stud is provided with an integral screw portion 28, and disposed contiguous to the surface of the molded member 24 is an 35 integral annular washer-like member 29 extending a substantial distance laterally of the stud. The edge of the member 29 may be serrated as shown in Figure 2 at 30, for facilitating engagement of a rotating tool. This washer-like member may also be provided with dimples 31 or 40 other deformations projecting into the molded member 24 for reducing any tendency of rotation between the molded member and the stud 26.

The threads of the screw 28 are preferably of a 45 relatively flat pitch, say about 18 threads per inch, and, although this screw may have a standard form of thread, such as U. S. Standard or V, it is preferred to use a special thread which is 50 relatively flat on its lower face 32. This thread may be what is known as a buttress thread, but in the embodiment shown in Figure 9, the lower face 32 has a slope of about 10° from a plane perpendicular to the axis of the thread, while the upper face 32' has a slope of about 30°. In the 55 standard buttress thread, one face is absolutely flat while the other face slopes at 45°. Such a thread facilitates ready engagement in the aperture provided in the steel plate 20, and, furthermore, improves the anchorage of the cleats.

60 As shown at 33 (Figure 4) the plate 20 is preferably tapped at appropriate points to receive the threaded studs 28, the tap being preferably of a pitch corresponding to that of the screw 28, whereby said screw will readily engage with said 65 aperture.

70 Shoes embodying my invention, as above described, have been put to severe tests and it has been found that cleats secured in the manner described are anchored so firmly that they cannot be dislodged or loosened, even when subjected to severe abuse.

75 Referring to Figure 5, there is here shown a shoe indicated generally by the numeral 50, which is suitable for golf, track, climbing, lumbering, and various other activities. This shoe comprises

upper 51, and a sole 52 carrying an embedded spring-steel plate 53. This shoe is provided with tread members 55 having a ground-engaging or spike portion 56, a threaded portion 57, and an intermediate annular or washer-like portion 58, 5 the edge of which may be serrated as at 59. The portion 57, as seen clearly in Figure 5, threadedly engages the metal plate 53, the latter being preferably tapped to receive it, as described above for the football shoe. 10

Figure 7 illustrates a baseball shoe sole 60 embodying my invention. In this case the sole tap 62 has secured thereto a tread member or "spike", indicated at 64, of the usual or other suitable design for baseball, said member being secured to 15 the sole by means of headed screws or studs 65 which extend through apertures in the spike 64 and in the sole and threadedly engage tapped apertures in a steel plate 67 embedded in the sole in a manner similar to the other embodiments. 20 Obviously, the heads of the screws 65 are disposed flush against the outside of the spike 64 so as to retain the latter firmly seated against the sole of the shoe.

While I have disclosed only a few embodiments 25 of my invention, it will be obvious that the latter may take numerous other forms and may be used for attaching cleats or treads of various other designs.

It will be obvious that although the treads are 30 secure against accidental detachment or displacement, they may readily be removed for replacement when broken or worn, or for converting a shoe for a different sport or activity, merely by unscrewing the old studs and applying new ones. 35 It will also be seen that shoes embodying my invention have maximum flexibility and lightness with perfect anchorage of the treads, and without any of the cumbersome auxiliary anchoring devices of the prior art, which add weight to the 40 shoe, reduce flexibility and entail possible injury to the foot of the wearer.

I am aware that it has previously been proposed to screw treads into a tapped metal plate of substantial thickness and weight and lacking 45 in flexibility, in a shoe sole (Borrett Patent 320,328, June 16, 1885). However, I believe that I am the first to secure a detachable tread to a thin, flexible metal plate in a shoe sole in the manner and for the purposes described. 50

Various other modifications will no doubt suggest themselves to those skilled in the art. Hence, I do not wish to be limited to the particular embodiments shown or uses mentioned except to the extent indicated by the appended claims, which 55 are to be interpreted as broadly as the state of the art will permit.

I claim as my invention:

1. An athletic shoe comprising a non-metallic tread member, a relatively thin spring steel plate 60 above and substantially coextensive with said member and having a plurality of threaded apertures, a non-metallic sole member engaging the upper surface of said plate, and ground-engaging elements engaging the exposed surface of said 65 tread member and having screws retained by engagement in said apertures and with said tread and sole members.

2. An athletic shoe comprising a non-metallic tread member, a relatively thin spring-steel plate 70 above said member and having a threaded aperture, a non-metallic sole member engaging the upper surface of said plate, and a ground-engaging element engaging the exposed surface of said 75 tread member and having a screw retained by en-

gagement in said aperture and with said tread and sole members.

3. An athletic shoe comprising a non-metallic tread member, a relatively thin spring-steel plate above said member and having an aperture formed for threaded engagement with a screw, and a ground-engaging element having a screw engaged in said aperture, the pitch length of said screw being greater than the thickness of said plate and said plate being engaged substantially entirely between the crests of consecutive turns of the thread of said screw.
- 10 4. An athletic shoe comprising a non-metallic

tread member, a relatively thin spring-steel plate above said member and having an aperture formed for threaded engagement with a screw, and a ground-engaging element having a screw engaged in said aperture, the pitch length of said screw being greater than the thickness of said plate and said plate being engaged substantially entirely between the crests of consecutive turns of the thread of said screw, a portion of said plate at said aperture being tilted upward in engagement with a downwardly facing side of the thread of said screw. 5
